UNITED STATES PATENT OFFICE.

CHARLES L. BURR AND HARRY MAKER, OF HIBBING, MINNESOTA.

FLY-CATCHER.

1,185,055.

Specification of Letters Patent. Patented May 30, 1916.

Application filed April 21, 1915. Serial No. 22,912.

To all whom it may concern:

Be it known that we, CHARLES L. BURR and HARRY MAKER, citizens of the United States, residing at Hibbing, in the county 5 of St. Louis and State of Minnesota, have invented certain new and useful Improvements in Fly-Catchers; and we do hereby declare the following to be a full, clear, and exact description of the invention, such as 10 will enable others skilled in the art to which it appertains to make and use the same.

This invention relates to means for catching flies and is in the nature of a fly catcher, comprising a strip of sticky paper or cloth 15 inclosed within an outer casing or box and constructed in an economical and efficient manner to carry out the several objects of the invention hereinafter mentioned.

The prime object of the invention is to 20 provide a device of this character, which, when ready for shipment or sale, is inclosed within a compact structure whereby it is protected against damage in handling and the user is protected against contact with the 25 sticky paper or cloth.

A further object of the invention is to 30 provide a device of the character specified which, while compactly inclosed as before specified, may be readily opened for use and 35 any desired length of the sticky strip withdrawn and severed, the case or box, with the remainder therein, being always left in condition to facilitate the ready withdrawal of more of the strip when desired.

With these objects in view, the invention 40 consists in the improved construction, arrangement and combination of the parts of a device of the character mentioned, which will be hereinafter fully described and afterward specifically claimed.

In order that the construction and operation thereof may be readily comprehended, an approved embodiment of the invention is 45 illustrated in the accompanying drawings, which will be now specifically described in connection with said drawings, in which,

Figure 1 represents, in perspective, the outer casing as it appears when the fly catcher is inclosed therein, ready for shipment or storage. Fig. 2 represents, in perspective, the same parts, with the strip partially withdrawn and the fastener in inoperative position. Fig. 3 represents, in transverse section, the parts shown in Fig. 1. 55 Fig. 4 represents the same parts in longi-

tudinal section, and Fig. 5 represents the juncture of two sections of the strip.

Like reference characters indicate the same parts wherever they appear in a plurality of the figures of the drawings. 60

Referring specifically to the drawings, the box, indicated at 100 is cylindrical and has a slot 11^a, as shown in the construction of Figs. 1 to 4. The adhesive strip 120 is coiled, as at 130, in the box and its end projects through the slot. The strip 120 is composed of sections, as at 120^a, 120^b, their ends being reduced transversely and perforated, as shown at 121 in Fig. 5, to facilitate their separation. 70

In the forward or outer end of each section is an eye, or eyelet, as at 122, 123, and when the strip is coiled within the box, as in Figs. 1 and 3, one section, as 120^a, projects just far enough out of the slot 11^a to permit 75 one end of an open locking ring 124 seated in a circumferential groove 125 around the box, to be passed through the eye 122 to hold the strip in position. When section 120^a has been torn off, section 120^b projects in like 80 manner, the ring 124 engaging in eye 123, as seen in Fig. 4, and securing the remaining sections in the box. To remove a strip, as 120^a, the ring 124 is turned to remove its end from the eye 122, the section drawn entirely out of the box and the section 120^b drawn out to bring its eye 123 in position 85 and the ring turned into eye 123, when the section 120^a can be torn off on the perforated line of juncture 121. 90

The box, illustrated in Figs. 1 to 4, is provided with an end 140 inclosed by a permanent cover 141, and a cover 142 at the opposite end of the box is removable for the purpose of inserting or removing the coiled adhesive strip. To facilitate the withdrawal of the strip through the slot, a hook 143, having a finger ring or eye 144 may be engaged in the eye, as 122 in Fig. 5. 95

From the foregoing, it will be observed 100 that we have provided a neat, handy package containing inclosed and protected strips of adhesive material, with ready means for opening the case and removing any portion desired for use at any time, the remainder 105 being retained within the case and protected for use when desired.

While the exact construction and arrangement of the parts of the invention have been specifically described in the foregoing, it 110

will be obvious to those skilled in the art to which the invention most nearly appertains, that slight changes and variations may be made therein without departing from the 5 spirit and scope of the invention.

Having thus fully described our invention what we claim as new and desire to secure by Letters Patent is:—

1. A fly catcher comprising a casing having a slot in its top, a roll of adhesive material within the casing consisting of sections separated by transverse lines of perforations, the end of the outer section being projected through the slot, and each section having an eye near its advanced end, and means at the advanced end of each section to facilitate its withdrawal through the slot, said means comprising a hook adapted to engage in the eye and provided 20 with a ring to receive a finger.

2. A fly catcher comprising a cylindrical casing having a longitudinal slot in one side, a strip of adhesive material coiled within the casing, having its outer end projected through the slot and provided with 25

an eye in the projecting portion, and an open ring mounted around the cylindrical casing and adapted to be turned upon the casing to pass one of its ends into and out of said eye.

3. A fly catcher comprising a cylindrical casing having a longitudinal slot in one side thereof, a roll of adhesive material within the casing consisting of sections separated by transverse lines of perforations, the outer sections being projected through the slot and each section being provided near its advanced end with an eye, and an open ring around the cylindrical casing in line with the eyes and adapted to 40 be moved into or out of said eyes by turning it upon the casing.

In testimony whereof we have signed our names to this specification in the presence of two subscribing witnesses.

CHARLES L. BURR.
HARRY MAKER.
